UNITED STATES PATENT OFFICE.

WILLIAM G. KENDALL, OF NEWARK, NEW JERSEY.

HINGE AND COMPACT HOLDER FOR VANITY CASES.

Application filed February 17, 1928. Serial No. 255,105.

This invention relates to vanity cases, and particularly to an improved hinge and compact plate holder, the object being to provide an improved structure wherein the holder 5 will act as part of the hinge structure for mounting the lid of the vanity case.

Another object of the invention is to provide an improved form of combined hinge and holder, wherein the cover of the vanity 10 case is supplied with a hinge knuckle and a wire ring mounted in the vanity case and interlocking with a shoulder therein acting in the double capacity of means for holding a compact in the vanity case and as a pintle 15 for the knuckle.

A further object of the invention is to provide in a vanity case, an improved form of ejector which assists in normally holding the compact in the vanity case while permitting a pull to cause the compact to be removed.

In the accompanying drawing—

Figure 1 is a longitudinal vertical sectional view through a vanity case provided 25 with an embodiment of the invention.

Figure 2 is a sectional view through Figure 1, approximately on line 2—2.

Figure 3 is a horizontal sectional view through Figure 2, approximately on line 30 3—3.

Referring to the accompanying drawing by numerals, 1 indicates the body of a vanity case, which may be round or other desired shape. A cap or lid 2 telescopically fits 35 over part of body 1 and acts as a closure therefor. Body 1 is provided with an annular pressed out member or bead 3 which presents an ornamental appearance on the outside, while presenting a groove on the 40 inside. This groove results in a shoulder 4 against which the holding ring 5 rests. The groove formed by the pressed out portion 3 is shown as part of a circle, but this could be square or the parts could merely be offset in the lower part of the body 1 so as to 45 present a shoulder 4. The particular formation of this part of the vanity case is of no importance if it is provided with some kind of a shoulder 4 so as to permit the ring 5 to interlock therewith and be held against an upward movement thereby. Ring 5 has 50 been shown round in cross section, but it could be rectangular or any desired shape without departing from the spirit of the invention. The ring is mounted preferably above

the compact pad plate 6 and acts to hold or lock this plate in the body 1. This compact plate could be in the nature of a disk or a cup member having any desired form of bottom and any desired form of upstanding flange for enclosing or receiving a pad 7. The lid 2 is provided with a plate 8 which may be soldered or otherwise rigidly secured thereto, and said plate in turn is formed with a curved portion 9 presenting a hinge knuckle through which part of the ring 5 projects, whereby the lid is really hingedly connected with the holding ring 5. However, the body 1 is provided with an aperture 10 through which knuckle 9 projects so that all the parts are connected together when the ring 5 is extending through knuckle 10. If desired, instead of having a separate plate 8, the lid 2 could be formed with an extension having a knuckle 9 as a part thereof.

In forming the ring 5, the same is preferably formed slightly less than a circle as shown in Figure 3, and the end sections 11 and 12 are bent upwardly or in a direction 80 parallel to the axis of the body 1. The ring 5 is preferably of resilient material, as for instance, metal, and when the members 11 and 12 are forced toward each other the ring will be constricted or contracted and will 85 thereby readily move from beneath the shoulder 4 so that the ring may be swung outwardly and thereby release the pad 6. Usually this is sufficient to permit the pad to fall out of the body when the body is inverted, but if desired, an ejecting member 13 may be used to positively remove the plate 6. This ejecting member is a ribbon, 90 tape or other flexible member having the body 14 extending centrally across the bottom of plate 6, and then upwardly for forming the pull tabs 15 and 16. From Figure 2 it will be observed that the plate 6 pinches part of the tape 13 against the side walls of body 1 and also against the under surface of the holding ring 5. In this way, the tape 13 acts as assistant holding means for holding the compact plate in position. After the ring 5 has been released, the pulls or extensions 15 and 16 may be grasped and the 95 tape pulled upwardly, whereupon the compact plate will be pulled out of body 1 or ejected therefrom. Preferably the tape 13 is a very small narrow piece of ribbon of a desired color, with the pulls 15 and 16 only 100

slightly overlapping the pad 7, whereby ordinarily it presents a pleasing appearance without being in the way.

What I claim is:

5. 1. A vanity case, comprising a body having a bottom and an upstanding annular wall formed with an opening therein appreciably below the upper edge thereof and an interiorly positioned annular depression in 10 the plane of the opening, a lid for said body adapted to telescope partially over said upstanding wall when closed, said lid being provided with a curled extension presenting a hinge knuckle, said extension projecting 15 through said opening, and a compact pad holding ring arranged in said annular depression for holding a compact in said body, said ring extending through said knuckle for completing the hinge structure.
  20. 2. In a vanity case provided with a body having an interior shoulder, a holding ring interlocking with said shoulder and provided with manually actuated means for constricting the ring whereby it may be removed 25 from said shoulder, said ring normally acting to hold a compact plate in said body, and a hinge knuckle surrounding part of said ring and connected with the lid of said vanity case whereby the ring acts in the capacity of a pintle for the lid hinge.
  30. 3. A hinge and compact holder for a vanity case, comprising a hinge knuckle extending from the lid of the vanity case, and a holding ring of resilient material positioned 35 to interlock with said vanity case for holding a compact therein, said ring being also formed with hand operated members for constricting the ring whereby it may be released from said vanity case, said holding 40 ring extending through said knuckle for completing the hinge structure.
  45. 4. In a vanity case provided with a body having a shoulder, of a resilient holding ring positioned to interlock with said shoulder, said ring projecting beyond the shoulder for engaging and holding a compact pad plate in said body, said ring being provided with a pair of parallel manually actuated members for constricting the ring and 50 thereby causing the ring to be released from said shoulder and said plate to be released from said ring.
  55. 5. In a vanity case provided with a body having a shoulder and an aperture adjacent the shoulder, of a hinge knuckle connected with the lid of the vanity case extending through said aperture, a resilient holding ring extending through said knuckle for 60 completing the hinge structure for the lid, said holding ring being positioned to interlock with said shoulder and project beyond the shoulder for engaging and holding a compact pad plate in said body.
  6. In a vanity case, a combined holding and ejecting member consisting of a flexible 65 tape-like member adapted to extend across the bottom of the vanity case and beneath the compact plate held therein and to a point above the side edges of the compact plate whereby when the ends of the tape-like 70 member are pulled, said compact plate will be removed from said body.
  7. In a vanity case provided with a body and a compact plate therein, a holding member for normally holding said compact plate 75 in the body, and an ejector formed as a tape-like member of cloth extending beneath the compact plate and above the plate at the respective ends of the tape-like member whereby when said holding member is moved to 80 a released position said tape-like member may be grasped and pulled for removing the compact plate from said body.
  8. A vanity case, comprising a body having an upstanding wall formed with an annular shoulder interiorly thereof and with a notch at one point adjacent said shoulder, a cover formed to telescopically fit over part 85 of said body, a hinge knuckle connected with said cover and extending substantially 90 through said notch, a resilient ring of wire extending through said knuckle for completing the hinge structure, said ring of wire fitting beneath said shoulder and locking a compact plate in said body, said ring being 95 provided with a pair of upstanding hand members capable of being actuated for constricting the ring so as to remove the same from beneath said shoulder and thereby release said compact plate.
  9. In a vanity case, a body having an upstanding wall and an annular internal groove whereby a shoulder is presented, and a resilient ring fitting into said groove and extending beyond the groove for holding a 105 compact plate in said body, said ring being open at one point and having projections at each end, said projections being capable of movement manually for constricting the size 110 of the ring so that it may be removed from said groove for releasing said compact plate.
- Signed at New York, in the county of New York and State of New York this 16th day of February, A. D. 1928.

WILLIAM G. KENDALL.
